INVENTOR

M. Evans

BY *Victor J. Evans*

ATTORNEY

WITNESS:

UNITED STATES PATENT OFFICE.

MARY KATHERINE ADCOCK, OF WINCHESTER, KENTUCKY.

WINDOW ATTACHMENT.

Application filed September 11, 1922. Serial No. 587,410.

To all whom it may concern:

Be it known that I, MARY KATHERINE ADCOCK, a citizen of the United States, residing at Winchester, in the county of Clark 5 and State of Kentucky, have invented new and useful Improvements in Window Attachments, of which the following is a specification.

This invention relates to window attachments and has for its object the provision of a novel device designed to be inserted at a partly open window for the purpose of permitting thorough ventilation without danger of rain or wind entering and causing 15 damage to surrounding objects, draperies and the like.

An important and more specific object is the provision of a shield of this character which is detachably connected with the sides 20 of a window casing and located below the partly raised lower sash, the device being located inside of the room and having an inclined wall which will deflect upwardly air blowing through the opening and thus preventing draft, the device being adjustable 25 to fit windows of different sizes.

An additional object is the provision of a device of this character which will be simple and inexpensive in manufacture, easy to install or remove, efficient and durable in use 30 and a general improvement in the art.

With the above and other objects and advantages in view the invention consists in the details of construction to be hereinafter 35 more fully described and claimed and illustrated in the accompanying drawings, in which:

Figure 1 is a perspective view of the device in applied position, and

40 Figure 2 is a detail section on the line 2-2 of Figure 1.

Referring more particularly to the drawings the letter A designates a portion of a window frame or casing within which are 45 slidably mounted the usual sashes B and C. The letter D represents the sill.

In carrying out my invention I provide a 50 ventilating device which may be constructed of sheet metal, wood, fiber or in fact any suitable material, painted, enameled or otherwise treated to present a pleasing appearance and to increase the durability. This ventilator shield consists of side members 10 and 10^a which are triangular or 55 wedge shaped and the former of which is formed upon a relatively large plate 11

which has its lower edge formed with an in-turned flange 11^a designed to rest upon the window sill D. The member 10^a is formed at one edge with spaced flanges 10^b which receive the free end of the plate 11, this construction enabling the device to be elongated or shortened whereby to fit windows of different sizes.

It is of course necessary to provide means 65 for holding this structure in place and to accomplish this I secure, upon the end members 10 and 10^a, upright springs 12 which have their upper and lower ends rolled as indicated at 13 and which have their intermediate portions formed with rings or loops 70 14 which will provide resilience. The upper rear corners of the end members 10 and 10^a are cut away as indicated at 15 so that the upper rolled ends 13 of the spring members 75 will extend beyond.

When it is desired to install the device, the lower sash B is raised partly to permit the members 10 and 10^a to be inserted beneath the lower edge thereof, the members 80 10 and 10^a being pulled apart until they engage against the confronting faces of the window frame or casing. The sash is then pushed down until it engages firmly against the rolled upper ends 13 of the springs 12. 85 The inherent resilience of these springs pressing against the sill and the sash will operate to hold the device firmly in position.

When the device has been constructed and installed as above described, it is apparent 90 that wind blowing beneath the sash will impinge against the inclined plate or sheet 11 and will be deflected upwardly toward the ceiling so that thorough ventilation will be insured and draft prevented. At the same time it is apparent that rain cannot enter 95 and that surrounding objects, such as articles of furniture, draperies and the like will not be injured.

While I have shown and described the 100 preferred embodiment of the invention it is of course to be understood that I reserve the right to make such changes in the form, construction, material and arrangement of parts as will not depart from the spirit of the invention or the scope of the subjoined claims.

Having thus described my invention I 105 claim:

1. A window attachment comprising a 110 shield device adapted for disposition below the partially raised lower sash and including end portions engaging against the con-

fronting sides of the window casing and connected by a relatively large plate portion inclined upwardly away from the window with its lower edge disposed upon the sill 5 and spring means for holding the device in position, said means consisting of a pair of spring members mounted at the edges of said end members and having one end engaging the sill and the other end engaging the lower edge of the bottom rail of the lower sash.

2. A window attachment comprising a shield device adapted for disposition below the partially raised lower sash and including 15 end portions engaging against the confront-

ing sides of the window casing and connected by a relatively large plate portion inclined upwardly away from the window with its lower edge disposed upon the sill and spring means for holding the device in 20 position, said means consisting of a pair of spring members mounted at the edges of said end members and having one end engaging the sill and the other end engaging the lower edge of the bottom rail of the lower sash, said spring members being formed intermediate their ends with loops providing constant resilience.

In testimony whereof I affix my signature.
MARY KATHERINE ADCOCK.
